UNITED STATES PATENT OFFICE.

JOSEPH C. DONNELLY, OF BARBERTON, OHIO, ASSIGNOR TO THE DIAMOND MATCH COMPANY, OF CHICAGO, ILLINOIS, A CORPORATION OF ILLINOIS.

MACHINE FOR PACKING MATCHES.

1,122,580.

Specification of Letters Patent. Patented Dec. 29, 1914.

Original application filed October 23, 1912, Serial No. 727,282. Divided and this application filed June 13, 1914. Serial No. 844,851.

To all whom it may concern:

Be it known that I, JOSEPH C. DONNELLY, a citizen of the United States, and resident of Barberton, in the county of Summit and State of Ohio, have invented certain new and useful Improvements in Machines for Packing Matches, of which the following is a specification.

In accordance with an official requirement, the invention forming the subject of the present case is divided out of my pending application, Serial No. 727,282, filed February 6, 1912.

This invention relates to machines for packing matches, with particular reference to the machine set out in Letters Patent of the United States No. 1,016,436, dated February 6, 1912.

The invention concerns devices of simple and efficient construction and operation for the purpose of positioning within the filled box trays any matches whose ends may be projecting over the sides of the trays.

The invention also comprises straightening and leveling means co-acting with the end positioning devices to effect the compact and orderly arrangement of the matches within the box trays, as will be hereinafter fully described and claimed.

In the drawings—Figure 1 is a vertical section of a portion of the tray-conveyer and adjuncts of a match packing machine embodying my invention, only so much of the machine being shown as is necessary to illustrate the invention. Fig. 2 is a sectional perspective view of the match positioning devices in closed or acting position and the tray lifters as provided with box trays and elevated. Adjacent portions of the filler trough, main bed plate and tray-conveyer are shown. Fig. 3 is a rear view of the positioning devices and their actuating parts, said devices being also shown in closed or acting position. Fig. 4 is a diagram illustrating by full lines the positioning blades as in open position, and the filled box-tray as in down position preparatory to its being raised into the path of the said

blades; and illustrating by the dotted lines the box-tray as raised and its projecting matches as engaged and positioned by said blades. Fig. 5 is a transverse section through the tray-lifters and the filled tray thereon, showing the vibratory blade for bearing upon and distributing and straightening the matches within the tray.

1 designates a part of the bed or table upon which the tray-conveyer 2 is supported and guided. This conveyer comprises an endless chain of links 3 provided on their under sides with gear teeth 4 with which mesh the teeth of the actuating gear wheels, of which one is indicated at 5, and on their upper sides with holders 6 for the box-trays 7.

8 designates a portion of the filler trough through which the matches are directed to a suitably-disposed discharge station above the path of the trays in the conveyer, which trough is rapidly vibrated in a manner to assist the passage of the matches therewith.

9 designates a pair of vertically-reciprocative channeled brackets adjacent the discharge station of the filler trough. These brackets are designed directly to receive and engage the ends of trays positioned therebetween by the conveyer, and to raise and lower such trays independently of their holders relatively to such discharge station. The brackets are supported by a rising and falling yoke frame 10 under the control of an appropriate cam on a driven shaft of the machine.

In the patented structure the devices for positioning within the filled trays any matches whose ends may be projecting beyond the sides of the trays after they leave the discharge station, include a pair of yielding diverging plates or blades between which the upper portion of a filled match tray is entered when it is raised by the channeled brackets as above-mentioned, which blades, together with an intermediate depending match settling plate, which bears transversely upon the matches within the

tray, are supported by a bracket secured to, and partaking of the longitudinal reciprocations of, the hopper.

In the present construction the blades are mounted independently of the hopper, and are arranged to swing toward and from the sides of the box tray in a manner to exert a direct endwise thrust upon match ends projecting laterally of the tray. These blades, indicated at 16, are secured at their upper ends to parallel rock-shafts 17 which are journaled in bearings 18 in a bracket frame 19 rising from the bed, said shafts being appropriately spaced to permit the requisite oscillation of the blades in respect to the filled box-tray raised between the same. The outer ends of the rock-shafts have secured thereto a pair of inwardly extending lever arms 20, the inner ends of which overlap and are pivotally jointed, as by a pin and slot connection 21, with a vertically-movable rod 22 mounted in perforated lugs on the bracket frame, the construction of the parts being such that the rod and its adjuncts tend normally to swing the blades 16 outward or away from each other, and that when the rod is raised the blades are caused to swing toward each other. The rod is provided with a toe 23 which extends into the path of one of the limbs of the vertically movable yoke frame 10 above referred to. This frame in its upward movement effects the elevation of the lifter brackets 9 and the filled match trays engaged thereby, one of the trays being raised toward the discharge station of the filler trough, and the other between the inner depending sides of the blades 16. As the yoke frame approaches the limit of its upward movement these blades extend laterally of and below the top of the tray, and the frame, impinging against the opposing toe 23, effects the inward swinging of the blades, which thereupon bear directly against the ends of the matches projecting over the edges of the tray and push them into the tray. Upon the descent of the yoke frame the filled tray is deposited in its holder on the conveyer, and the blades and their connections resume their normal position by gravity ready for a repetition of their operation upon the endwise projecting matches of a succeeding tray.

Arranged midway between the blades is a match straightening plate 24 which is secured to a bracket 25 on the vibratory trough so as to partake of the action of the latter. The lower edge of this plate is serrated, and is so disposed that when the filled tray is raised between the swinging blades 16, such serrated edge bears upon the top of the matches and by its reciprocations thereon serves to distribute and compact them uniformly within the tray, substantially as de-

scribed in the Patent No. 1,016,436 afore- 65 said.

I claim—

1. In a machine for packing matches, the combination with means for feeding match receptacles, of a pair of blades laterally movable relatively to each other, a support therefor, means for raising and lowering the receptacles in a path between the blades, and devices actuated by the last-named means for moving the said blades toward 75 and from the sides of the receptacles presented therebetween.

2. In a machine for packing matches, the combination with means for feeding match receptacles, of a pair of normally-open 80 blades laterally movable relatively to each other, a support therefor, a connection between said blades, and means for raising and lowering the receptacles in a path between the blades, said last-named means in its upward stroke actuating said connection to move the blades toward the sides of the receptacles presented therebetween.

3. In a machine for packing matches, the combination with means for feeding match 90 receptacles, of a pair of blades laterally movable relatively to each other, a support for said blades, means for raising and lowering the receptacles in a path between the blades, devices actuated by the last-named 95 means for moving the said blades toward and from the sides of the receptacles presented therebetween, and a member located between said blades adapted to bear upon the contents of said receptacles. 100

4. In a machine for packing matches, the combination with means for feeding match receptacles, of a pair of blades, laterally movable relatively to each other, a stationary support therefor, a vertically-disposed plate between the said blades, means for raising and lowering the receptacles in a path between the blades and beneath the plate, means whereby the said blades are moved toward and from the sides of the receptacles presented therebetween, and means whereby the said plate is horizontally jarred. 110

5. In a machine for packing matches, the combination with means for feeding match receptacles, of a supporting element, a pair of blades mounted to oscillate on said element, means for raising and lowering the receptacles in a path between the blades, and devices actuated by the last-named means for causing the said blades to swing toward 115 and from the sides of the receptacle presented therebetween.

6. In a machine for packing matches, the combination with means for feeding match receptacles, of a supporting element, a pair 125 of blades mounted to oscillate on said element, means for raising and lowering the receptacles in a path between the blades, de-

vinces actuated by the last-named means for causing the said blades to swing toward and from the sides of the receptacles presented therebetween, and a member located between 5 said blades adapted to bear upon the contents of said receptacles.

Signed at Barberton in the county of

Summit and State of Ohio this 10th day of June A. D. 1914.

JOSEPH C. DONNELLY.
